UNITED STATES PATENT OFFICE.

EDWARD A. LANGENBACH, OF CANTON, OHIO.

DESIGN FOR A METALLIC FINISHING-PLATE.

SPECIFICATION forming part of Design No. 23,224, dated April 24, 1894.

Application filed March 20, 1894. Serial No. 504,458. Term of patent 7 years.

To all whom it may concern:

Be it known that I, EDWARD A. LANGENBACH, a citizen of the United States, and a resident of Canton, county of Stark, State of Ohio, have invented and produced a new Design for Metallic Finishing-Plates for Buildings, of which the following is a full, clear, and exact description, reference being had to the accompanying drawings, making part of this specification.

Figure 1 is a plan view and Fig. 2 a section on a line from x to x .

My design consists of a square or rectangular metallic finishing plate A, divided into sub-divisions by series of short broken or intercepted oval ribs or projected portions a and b , extending across the plate on lines at right angles to each other, and rosettes or circular projections d , situated at a point

where the ribs a and b would cross if continued, and the open space between the ends of the ribs and the rosette.

The essential features of my design are a metallic finishing plate divided into sub-divisions by series of sectional or intercepted ribs, at right angles, the circular projections d , and the open space between the ends of the ribs, and the raised circular projection.

What I claim is—

The design for a metallic finishing plate 30 herein shown and described.

In testimony whereof I have hereunto set my hand this 13th day of March, A. D. 1894.

EDWARD A. LANGENBACH.
